Primary Examiner — Mary Ann Calabrese*Assistant Examiner* — Catherine Ho(74) Attorney, Agent, or Firm — Moreno IP Law LLC(57) CLAIM

I claim the ornamental design for a table base, as shown and described.

DESCRIPTION

FIG. 1 is a perspective view of a table base showing my new design
FIG. 2 is a top plan view thereof.

FIG. 3 is a bottom plan view thereof.

FIG. 4 is a front side elevational view thereof.

FIG. 5 is a back side elevational view thereof.

FIG. 6 is a left side elevational view thereof; and,

FIG. 7 is a right side elevational view thereof.

The broken lines showing a glass top in the figures depict environment matter and form no part of the claimed design.

1 Claim, 5 Drawing Sheets(56)
